(57) **CLAIM**

The ornamental design for a solar powered lamp simulating a pebble stone, as shown and described.

DESCRIPTION

FIG. 1 is a front elevational view of a solar powered lamp simulating a pebble stone showing my new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof; and,
FIG. 7 is a perspective view thereof.
The broken lines shown form no part of the claimed design.
